The ornamental design for a tablecloth clip, as shown and described.

DESCRIPTION

FIG. 1 is a perspective view of a tablecloth clip showing my new design;

FIG. 2 is a rear elevational view thereof;

FIG. 3 is a front elevational view thereof;

FIG. 4 is an auxiliary view thereof, the same taken substantially along the plane 4—4 of FIG. 3;

FIG. 5 is left side elevational view thereof;

FIG. 6 is a right side elevational view thereof;

FIG. 7 is a top plan view thereof;

FIG. 8 is a front elevational view thereof with a lower pivot arm in an open operative position for engaging the underside of a tabletop;

FIG. 9 is a sectional view thereof, the same being taken substantially along the line 9—9 of FIG. 8; and,

FIG. 10 is a sectional view thereof, the same being taken substantially along the line 10—10 of FIG. 8.

The broken line showing of a spring depicts environment only and forms no part of the claimed design. In FIGS. 4 and 5 the surface within the broken lines forms no part of the claimed design.
